MACHINE FOR APPLYING PATCHES TO FABRICS

Theodore Finke, Euclid, Ohio

Application May 5, 1955, Serial No. 35,822

Term of patent 14 years

(Cl. D55—1)

Fig. 1.

Fig. 2.

Fig. 1 is a front perspective view of a machine for applying patches to fabrics embodying my new design; and

Fig. 2 is a perspective view of the machine, as viewed from the right side thereof.

The machine, as viewed from the left side thereof, is substantially the same as the machine as viewed from the right side thereof.

I claim:

The ornamental design for a machine for applying patches to fabrics, substantially as shown and described.
